UNITED STATES PATENT OFFICE.

ABD-EL-RAHMAN AMER KHALIFAH, OF DELENGAT, EGYPT.

PERPETUAL CALENDAR.

Application filed October 29, 1923. Serial No. 671,494.

To all whom it may concern:

Be it known that I, ABD-EL-RAHMAN AMER KHALIFAH, a subject of the King of Egypt, and residing at Delengat, Egypt, have 5 invented certain new and useful Improvements in a Perpetual Calendar, of which the following is a specification.

This invention relates to improvements in perpetual calendars.

10 The primary object of this invention is the provision of a perpetual calendar by means of which a person may ascertain to a certainty the relation of the days of the week to calendar months for any year or century.

15 A further and important object of this invention is the provision of a perpetual calendar by means of which it is possible to designate the day of the week for any date in a given year or century.

20 A further object of this invention is the provision of a practical calendar, which is easy of operation, and which is compact, embodying features which render the same practical as a convenience in every day life 25 or business, and which possesses exceptional features making the same valuable for educational, historical, and scientific purposes.

Other objects and advantages of this invention will be apparent during the course 30 of the following detailed description.

In the accompanying drawings, forming a part of this specification, and wherein similar reference characters designate corresponding parts throughout the several views.

35 Figure 1 is a front elevation of the improved calendar, showing the relation of parts thereof.

Figure 2 is a rear elevation of the calendar, showing the relation of parts thereof, in cooperative position with the arrangement of parts illustrated in Figure 1 of the drawings.

40 Figure 3 is a cross sectional view taken substantially on the line 3—3 of Figure 2.

45 Figure 4 is a cross sectional view taken substantially on the line 4—4 of Figure 1.

Figure 5 is an elevation, partly in cross section, taken on the line 5—5 of Figure 3, showing cooperating features of this invention.

50 Figure 6 is an elevation, partly in cross section, taken substantially on the line 6—6 of Figure 3.

55 Figure 7 is a cross sectional view taken substantially on the line 7—7 of Figure 3.

Figure 8 is a fragmentary view, partly

in section, showing a novel cooperating arrangement of details of this invention.

In the drawings, wherein for the purpose of illustration is shown but the preferred embodiment of this invention, the letter A 60 may generally designate the improved perpetual calendar, which may include a frame B formed in any approved manner to receive the movable portions of this invention to be 65 subsequently mentioned.

By way of example, if the frame B is constructed of card board or analogous material, the frame B may comprise a main supporting plate or portion 15, upon the front face of which 70

may be attached in fixed relation therewith a thinner strip or plate 16, which is adapted to receive a plurality of numerals in calendar formation, substantially as is illustrated in Figure 5 of the drawings. This arrangement 75

of numerals, which may be designated by the reference character 17 is preferably such that thirteen vertical columns of figures are provided; the arrangement of numerals, in fact, providing two complete calendar arrangements, with the middle vertical column of figures as a common column; this vertical column of figures in the middle of the arrangement 17 having the numeral 1

therein which designates the first day of the 85 month. This plate or portion 16 is preferably provided with a slot or opening 19 therein, which receives a slide 21, which may be designated as a mask, and which moves laterally across the plate 16 in the opening 90

19 provided therefor, in order to hide certain of the numerals of the arrangement 17, as will be subsequently described. These numerals which the mask or slide 21 is 95

adapted to hide are delineated upon the exposed face or surface of the main plate 15 of the frame B which is displayed through the opening 19, although the numerals which are so displayed upon the plate 15 are 100

a continuation of the calendar numeral arrangement 17, as will be apparent.

The frame B furthermore includes upper and lower strip portions 25 and 26, which are provided along the upper and lower edges of the frame B, to provide transverse slots 105

27 in the frame B, within which a member or plate 28 is slidably mounted for transverse sliding through the frame B. This slide plate 28 may be provided with a rectangular or other shaped opening 30 there- 110 in which is of such size as to only expose seven of the vertical columns of the numeral

arrangement 17 of the plate 16 therethrough; this portion of the numeral arrangement 17 designating a calendar month. A strip 32 may be fixedly carried by the slide plate 28, at the upper portion of the opening 30, which normally lies in the same plane as the portion 16 of the frame B, and which has delineated thereon the days of the week in the ordinary calendar arrangement. It is thus seen that as the slide 28 is moved back and forth, the strip 32 will move therewith so that the numeral 1 of the calendar system of numerals 17 may be placed under any particular day of the week as delineated on the strip 32. A forward extension 35 is provided in fixed relation with the frame B, which extends outwardly through a transverse slot 36 in the slide cover or member 28, and the length of which slot 36 defines the amplitude of transverse movement of the slide or member 28, as the end edges of the slot 36 contact against the ends of the projection or extension 35.

It is to be noted that the slide plate 28 also covers the transversely movable member 21. However, the adjustment of the mask or slide 21 is accomplished by means of a finger engaging extension 38, which projects in a T-shaped cross section as a part of the slide 21, through an elongated slot 39 provided in the slide member or cover 28. Stop lugs 40^a may be provided in fixed relation with the frame B, to limit the amplitude of movement of the mask 21; each lug 40^a extending through the slot 39 for abutment with the ends of the extension 38, substantially as is illustrated in Figure 1 of the drawings. The purpose of this mask or slide member 21 is obvious, since it can be utilized to cover the numerals 29, 30 and 31 of the calendar arrangement 17, so that when the month of February is exposed, the calendar arrangement can be used to indicate the correct number of days in the month of February, which except during a leap year, discloses 28; the mask 21 in this instance covering the numerals 29, 30 and 31, merely by transversely sliding the same across the frame so that it will cover these numerals 29, 30 and 31. The slide or mask may also be used to cover the numerals 31 of the arrangement 17, when a month is exposed on the improved device A which has only 30 days therein, in contra-distinction to a month of 31 days; this arrangement of the calendar being illustrated in Figure 1, wherein the mask 21 is properly adjusted to cover the numerals 31.

A transversely slidable member 40 is carried in the frame B, in a slot 41 at the top of the frame plate 15, which has a front flap portion 42 upon the forward surface of which are delineated the months of the year in the novel arrangement illustrated in Figures 1 and 5 of the drawings. This arrange-

ment of months delineated on the member 40 is preferably such that the months are arranged in thirteen vertical columns. An opening 45 is provided in the plate 16, through which are exposed seven of the vertical columns of month delineations, at any one time. These months are arranged in a novel formation, so that the months in which the first falls on the same day of the week in any year which begins with March and ends with February are placed in the same vertical column. For instance September and December of such a year each start on the same day of the week, as do also June and February; March and November; May and January; and April and July. Thus, the seven vertical columns which are exposed through the openings 45 will display the twelve months of the year. A handle and indicating piece 47 is preferably fixedly connected to the member 40, and is exposed on the rear of the frame B, so that the member 40 may be readily transversely shifted in cooperative relation with other features of this invention to be subsequently described.

The slide cover 28 is preferably provided with a central indicating opening 50^a thereon, upwardly of the opening 30 therein, and upon opposite sides of which opening 50^a elongated slots or openings 51^a and 52^a are provided. These openings 50^a, 51^a and 52^a may be suitably covered by any protecting material, such as celluloid, and this celluloid may be contrasted in order that the celluloid which covers the openings 51^a and 52^a is less transparent than that which covers opening 50^a, so that the months which are exposed through the openings 50^a may be easier seen. Of course, the openings 51^a and 52^a are primarily adapted to expose all of those months which are designated on the member 40 as exposed through the slot 45 of the frame plate 16, and as is illustrated in Figures 1 and 5 of the drawings.

A vertical slot or opening 50 is provided in the rear plate 51 of the frame B, and in the lower portion of this opening 50 a plate or member 52 is fixedly placed, upon which is arranged a series of delineations designating centuries. On this member 52 the centesimal years from 1500 onward are shown in a certain spaced column arrangement, which has been shown to take care of those centesimal years which are divisible by 400, and which of course according to the Gregorian calendar are designated leap years. Prior to October 5, 1582, when the Julian calendar was in effect, every fourth year was a leap year, including all centesimal years divisible by four. Accordingly, the centuries prior to 1500 are designated in consecutive column arrangement.

Above the member 52, and just rearwardly of the frame rear plate 15, a plate or mem-

ber 54 is provided, which is transversely slidable across the calendar device A, and which has placed upon the rear surface thereof thirteen vertical columns of numerals. Only seven of these columns are visible through the slot or opening 50 of the frame plate 51 at any one time, and these numerals which are so visible designate the years in any century from the 10 first year in that century to the 99th year. The years consecutively read from left to right transversely across the member 54, and preceding each year which is divisible by four is a blank space, which 15 has been so arranged because of the fact that every fourth year in the century is a leap year, and in order that this year slide member 54 may cooperate with the century plate 52 and the slidable month bearing plate 40, 20 as will be subsequently described.

In connection with the retention of the handle and indicator member 47 in a definite relation with the year bearing member 54, and with respect to the frame B, a 25 series of substantially V-shaped teeth 57 are provided along the lower edge of the slot 41, over which a socket tab 58 of the month bearing member 40 may selectively engage to maintain the member 40 in a definite relation in the frame B, and as is illustrated in Figure 7 of the drawings. This 30 socket member 58 is placed just forwardly of the tab, indicator, or handle member 47, and is to be considered a part of the member 35 40. In this connection it is to be noted that in order to adjust the member 40 it will be necessary to vertically lift the socket piece 58 out of engagement with the teeth 57, in order to transversely slide the same into a 40 desired position. For this operation the user grasps the handle 47. To maintain the member 40 in a locked position within the frame B, a hinged flap 60 is provided upon the frame, the lower edge of which when it 45 is closed engages the top edge of the handle 47, so that it is impossible to elevate the member 40 to transversely slide the same. As a means of facilitating the transverse sliding of the year bearing member or slide 50 54, a transverse projection or handle 62 is provided, which may engage the sides of the slot 50 to limit the amplitude of movement of the member 54 across the slot; this 55 portion 62 providing also an indicator for the century member 52, as will be described.

Referring to the operation of this invention, by way of example, assuming that it is desired to set the device for the month of September in 23 year of the centesimal year 60 of 1900, the operator upon the rear side of the calendar device A will adjust the year bearing slide or member 54 so that the indicator or handle projection 62 is located directly over the centesimal year 1900. The 65 next operation will be that of transversely

adjusting the month bearing member 40 according to the already positioned year bearing slide or member 54. This operation is effected by lifting the hinged flap 60 until it is possible to elevate the slide 70 40 and transversely adjust the same so that the handle or indicator 47 thereof is disposed over that particular vertical column of the exposed years on the slide 54 in which the numeral 23 appears, which designates the 23rd year of the centesimal year 1900. When this relation has been arranged the member 40 may be lowered so that the socket flap or portion 58 is engaged over the proper tooth 57, substantially as is illustrated in the drawings, and the flap 60 is lowered to lock the slide 40 in place. Upon the front of the calendar arrangement A it will now be seen that the months which are exposed have the month 75 of September in the column on the extreme left. This fact can be readily determined, because all of the months which are exposed through the slot 45 of the frame plate 16 are also exposed through the transparent 80 openings 51^a and 52^a on the front cover or slide plate 28. The next operation is that of transversely adjusting the slide cover of plate 28 until the central opening 50^a thereof exposes the month of September 85 there-through. Knowing that the month of September contains 30 days, as is indicated by proper indicia above the particular month, the mask slide 21 may then be transversely 90 adjusted until the same covers the exposed numeral 31; leaving the calendar month of September for the year 1923 exposed through the opening 30 of the cover plate 28. As above mentioned the months are 95 arranged on the member 40 for a year 100 which begins with March. Thus, it is not necessary to shift the member 40 in the frame for the months January and February of a succeeding year. That is, assuming the member 40 is set for the year 1923, 105 it need not be shifted for the months January and February of 1924. The changing 110 of the months bearing member 40 is done on March 1.

From the foregoing description of this 115 invention it is apparent that a perpetual calendar has been provided, in which the scope of operation is unlimited. It is virtually possible for any person to determine the exact day of the week for any date 120 from the year 1 A. D. up through the centuries. The advantages of such a perpetual calendar are obvious, not only in connection with every day business, but particularly from an educational, historical, and scientific standpoint. The perpetual calendar is a mechanical device, requiring merely mechanical movement in order to effect the calculation thereof, in contradistinction to the analytic means of deter- 125 130

mining dates which has been heretofore relied upon when it was deemed expedient to determine the particular week day of any historical event, or astronomical phenomenon or the like.

Various changes in the shape, size, and arrangement of parts may be made to the form of invention herein shown and described, without departing from the spirit of this invention or the scope of the claims.

I claim:

1. In a perpetual calendar the combination of a frame, a century bearing member fixed in the frame, a year bearing member adjustable in the frame having the years from 1 to 99 indicated therein, a month bearing member adjustable with respect to the year bearing member so that the same may be arranged in the frame in a definite relation to a particular year of the year bearing member, a numeral bearing member having numerals thereon arranged in substantially calendar formation and in fixed relation with said frame, a member adjustable upon said frame having the week days delineated thereon, and means for arranging said week days according to a particular month of said month bearing member, said last mentioned member when so arranged having the numerals of the numeral bearing member correctly exposing the numerals of the calendar month indicated by said member.
2. In a calendar device the combination of a supporting frame, a system of numerals carried by said frame in substantial calendar formation, a month supporting member adjustably carried by said frame and adjustable with respect to said numerals, and a slideable cover plate carried by said frame adapted to expose a particular month of the month bearing member and the proper system of numerals for said month, said slideable cover member having the days of the week delineated thereon in correct relation to the month and numerals exposed thereby.
3. In a calendar device the combination of a supporting frame, a system of numerals carried by said frame in substantial calendar formation, a month supporting member adjustably carried by said frame and adjustable with respect to said numerals, and a slideable cover plate carried by said frame adapted to expose a particular month of the month bearing member and the proper system of numerals for said month, said slideable cover member having the days of the week delineated thereon in correct relation to the month and numerals exposed thereby,

said month bearing member having the month thereof which has the first day thereof falling on the same day of the week adjacently disposed in cooperating relation.

4. In a device of the class described the combination of a supporting frame, a system of numerals arranged in calendar arrangement on said frame, a cover plate adjustable across said frame having an opening therein through which the numerals may be exposed in correct calendar formation, means for arranging the cover plate and the system of numerals so that a month of 28, 29, 30 or 31 days may be exposed through said opening, a member carried by said calendar having centuries designated thereon in cooperative manner according to the Julian and Gregorian calendars, a member transversely slideable on said frame having a series of numerals thereon adapted to be exposed through an opening provided in said frame to designate the years 1 to 99 of any particular century, a month bearing member slideable in said frame, means for locking the month bearing member in a definite relation with a particular year of the year bearing member, said month bearing member when so disposed adapted to have a particular month displayed by the first mentioned adjustable member in cooperative relation to the system of numerals displayed through the opening of said member.

5. In a calendar arrangement the combination of a plate having a system of numerals arranged thereon in calendar formation up to and including the numeral 28, a second plate disposed rearwardly of the first mentioned plate and having numerals designated on a face of said plate rearwardly of the plane of the face of the first mentioned plate; said numerals on the second mentioned plate being the numerals 29, 30 and 31, a member having an opening therein adapted to expose the numerals of said plates, a strip carried at a marginal edge of this opening and so positioned that the said strip lies in the same plane as the first mentioned plate, said strip having designated thereon the days of the week in a cooperative arrangement with respect to the arrangement of numerals on said plates, and a mask slideable over the second mentioned plate and in the same plane with the first mentioned plate adapted to control the exposure of the numerals 29, 30, and 31 on said second mentioned plate.
